Patented Nov. 29, 1960

189,386

AIR CUSHION VEHICLE

Melville W. Beardsley, Severna Park, and Philip W. Jackson, Jr., Silver Spring, Md., assignors to National Research Associates, Inc., Laurel, Md., a corporation of Maryland

Filed Mar. 16, 1960, Ser. No. 59,760

Term of patent 14 years

(Cl. D71—1)

FIG. 1.

FIG. 2.

FIG. 3.

Figure 1 is a top plan view of an air cushion vehicle showing our new design;

Figure 2 is a side elevational view thereof; and

Figure 3 is a front elevational view thereof.

Dominant features of the design reside in the portions shown in full lines.

What is claimed is:

The ornamental design for an air cushion vehicle, as shown and described.
